UNITED STATES PATENT OFFICE.

CHARLES L. DREHER, OF LANCASTER, PENNSYLVANIA.

DESIGN FOR A HANDLE FOR CANES, UMBRELLAS, &c.

SPECIFICATION forming part of Design No. 19,845, dated May 20, 1890.

Application filed April 16, 1890. Serial No. 348,237. Term of patent 3½ years.

To all whom it may concern:

Be it known that I, CHARLES L. DREHER, of Lancaster, in the county of Lancaster and State of Pennsylvania, have invented certain new and useful Improvements in Designs for Cane and Umbrella and Parasol Handles; and I do hereby declare the following to be a full, clear, and exact description of the invention, such as will enable others skilled in the art to which it pertains to make and use it, reference being had to the accompanying drawing, which forms part of this specification.

My invention relates to an improvement in designs for cane, umbrella, and parasol handles; and it consists in the representation of a trunk or branch of a tree having a forked upper end, and around which trunk or branch is wrapped the tail of a snake, the head of the snake being shown as resting upon the upper end of the forked portion, and its body being curved so as to form the rounded portion of the handle, as will be more fully described hereinafter.

The accompanying photographic illustration represents the side elevation of a handle which embodies my invention.

A represents the trunk or branch of a tree, which is pronged or divided at the upper end, as shown, and which trunk or branch extends from the rounded smooth portion C, as shown. Resting upon the upper forked ends B of the part A is the head of a serpent D, and its body is curved upward and downward, so as to form the curved portion G of the handle, and the tail of the serpent is wound around the lower end of the part A, as shown. The head of the serpent or snake is inclined upward, as shown, and upon the end of the tail are formed a number of rat-tails.

Having thus described my invention, I claim—

The design for a cane, umbrella, or parasol handle, substantially as shown and described.

In testimony whereof I affix my signature in presence of two witnesses.

CHAS. L. DREHER.
